UNITED STATES PATENT OFFICE.

JOHN R. ZEISER AND ADLOW ZEISER, OF BERWICK, PENNSYLVANIA.

FORM FOR CONCRETE SIDEWALKS.

No. 872,602.

Specification of Letters Patent.

Patented Dec. 3, 1907.

Application filed July 17, 1907. Serial No. 384,240.

To all whom it may concern:

Be it known that we, JOHN R. ZEISER and ADLOW ZEISER, citizens of the United States, residing at Berwick, in the county of Columbia and State of Pennsylvania, have invented certain new and useful Improvements in Forms for Concrete Sidewalks, of which the following is a specification.

In constructing side walks of concrete it is generally necessary to set up confining strips, which are usually held in place by pegs driven into the earth and in order to allow for contraction and expansion, the walk is subdivided into blocks, either by cuts or by 15 interposing strips of felt or the like.

The present invention has for its object to facilitate and cheapen the construction of concrete side walks and to save material.

In accordance with this invention, rails or strips are arranged along opposite edges of the line of prescribed walk, and said strips are connected by tie plates which also serve to separate the walk into sections, the parts being of such construction as to admit of the 25 tie plates and confining strips being readily removed and easily and quickly placed in position as the work progresses.

For a full understanding of the invention and the merits thereof and also to acquire a 30 knowledge of the details of construction and the means for effecting the result, reference is to be had to the following description and accompanying drawings.

While the invention may be adapted to 35 different forms and conditions by changes in the structure and minor details without departing from the spirit or essential features thereof, still the preferred embodiment is shown in the accompanying drawings, in 40 which:

Figure 1 is a perspective view of a concrete walk embodying the invention. Fig. 2 is a horizontal section of a portion of the walk on the line x—x. Fig. 3 is a detail view 45 of a tie plate. Fig. 4 is a modified form of tie plate.

Corresponding and like parts are referred to in the following description and indicated in all the views of the drawings by the same 50 reference characters.

In accordance with this invention, after the bed of the walk has been prepared in the usual manner, confining strips 1 are placed along the sides thereof and are joined by tie 55 plates 2, the latter being spaced apart a distance corresponding to the length of the

blocks or sections. The strips 1 may be of any length, width and thickness and are usually wooden rails approximately two by four inches and of any length.

60

The tie plates 2 are of metal and are approximately one-fourth of an inch thick and approximately six inches wide and may be of a length corresponding to the width of the walk. The tie plates are formed in each end 65 with openings 3 to receive the confining strips over which they are fitted, thereby preventing lateral movement of said strips and holding them both against outward or inward displacement. A notch 4 is formed 70 in the outer vertical edge of the plate bordering upon the opening 3 and is designed to receive a wedge or key 5 by means of which the tie plates and confining strips are held in place. By having the notches 4 formed in 75 the outer edges of the portions of the plates bordering upon the openings 3, the wedges or keys 5 are located wholly exterior to the confining strips and may be readily tightened or loosened. The tie plates 2 in addition to retaining the confining strips 1 in 80 place also serve to subdivide the walk into blocks or sections, whereby provision is had for contraction and expansion without allowing the walk to crack or break irregularly, 85 which would be the case if no provision were had for contraction and expansion by separating the continuous walk into blocks or sections.

The confining strips 1 and the tie plates 2 90 constitute in effect a form for receiving the concrete or like material employed in the formation of the walk, said material after being mixed in the usual way and filled into the space between the confining strips and 95 tie plates, being tamped, flushed and troweled in the accustomed way. After the walk has set sufficiently to admit of the confining strips and tie plates being removed with safety, the wedges or keys 5 are driven 100 from the notches 4 and the tie plates lifted, after which the confining strips may be easily separated from the walk, the spaces formed by the tie plates being finished in any desired way. It will be understood that 105 there is no necessity or occasion for pinning the confining strips to the ground by the usual pegs, hence the said strips may be easily removed without disturbing the walk and used repeatedly.

In the modification shown in Fig. 4, the tie plate 2 is reduced in width, intermediate

110

of its end portions to admit of its upper edge coming in the plane of the top edge of the confining strips so that in constructing a sidewalk, the surplus material may be moved 5 from one section to the next adjoining section by brushing the same over the upper edge of the plate.

Having thus described the invention, what is claimed as new is:

- 10 1. A form for use in constructing side walks of concrete or like material, the same comprising spaced confining strips, tie plates having slots near their ends extended transversely thereof in an upward direction from 15 their lower edges to receive said confining strips by slipping over their upper edges, and having transverse notches in the outer vertical edges of the said slots, and keys adapted to be driven into said notches after securing 20 the tie plate and confining strips.

2. A form for use in constructing side walks of concrete or like material, the same comprising spaced confining strips and tie plates having their upper edges in the plane of the upper edges of said confining strips 25 and having their end portions widened and formed with slots extended through the lower edges of the said tie plates and adapted to slip over the confining slips, the outer vertical edges of said slots having transverse 30 notches, and keys adapted to be driven into said notches to secure the tie plates and confining strips.

In testimony whereof we affix our signatures in presence of two witnesses.

JOHN R. ZEISER. [L. S.]
ADLOW ZEISER. [L. S.]
